DOMESTIC APPLIANCE

John B. Dyer, Dayton, Ohio, assignor to General
Motors Corporation, Dayton, Ohio, a corpora-
tion of Delaware

Application June 6, 1938, Serial No. 212,258

3 Claims. (Cl. 68—23)

This invention relates to domestic appliances. It is an object of this invention to provide a washing machine which is capable of performing the washing operation and the drying operation in the same tub.

Another object of this invention is to provide a washing machine in which all of the washing, drying and rinsing operations can be automatically performed in the same vertically disposed tub.

Still another object of this invention is to provide a washing machine having a vertically movable agitator and a spinner tub in which the vertically movable agitator spins with the tub.

Further objects and advantages of the present invention will be apparent from the following description, reference being had to the accompanying drawing, wherein a preferred form of the present invention is clearly shown.

In the drawing:

Fig. 1 is a vertical cross-section of a washing machine embodying my invention; and

Fig. 2 is a fragmentary sectional view taken on line 2—2 of Fig. 1.

The washing mechanism includes a tub 14, which is preferably imperforate, except that at the upper rim 15 proper openings are provided so that the liquids can be discharged centrifugally into the drain trough 16 formed on the inside of the casing 10.

Inside of the tub 14 is provided a vertical cone-shaped agitator 17, which is provided at its lower extremity with flexible rubber-like ring 18, and is sealed to the bottom of the tub 14 by means of the metallic Sylphon or other type of bellows 19. The agitator 17 preferably is given a vertical reciprocating movement of about 1½ inches to 2 inches, at a speed of about 450 pulsations per minute. Preferably the tub 14 is about 20 to 25 inches in diameter at the top.

Proper mechanism is provided for vertically reciprocating the agitator 17 and centrifugally rotating the tub 14. This includes the motor 20 provided with a drive shaft 21 on which, are loosely mounted a pinion 22 and a worm gear (not shown) just behind the spiral gear 23. An agitator clutch 24, and a spinner clutch 25 are also mounted on the drive shaft 21, so that, by means of the clutch control rod 26, the motor can be drivingly connected either to reciprocate the agitator 17 or to spin the tub 14.

The agitator drive includes a gear 27 which meshes with the pinion 22 and is connected by the shaft 28 with the crank-pin 29. The pin 29 is connected to the Scotch yoke 30 which recipro-

cates vertically the agitator shaft 31 which extends up to and is connected with the agitator 17.

The spinning drive includes the worm gear 5 heretofore described which is connected to the spiral gear 23. The gear 23 is connected to the spinner shaft 32 which is coaxial with the agitator shaft 31. The spinner shaft 32 supports at its upper end the tub 14.

10 Proper gear casing arrangement is provided for the driving mechanism as shown. An upper bearing 33 is provided at the upper end of the gear casing to position the spinner shaft 32 while a complementary lower thrust bearing 34 is placed just above the spiral gear 23. The Scotch yoke 30 provided at the lower end of the shaft 31 is provided with an extension 30a which is guided in the lower longitudinal bearing 35.

The gear casing is divided a short distance below its top by means of the bolted flanges 36. In order to simplify this disclosure, the means for supporting the gear casing within the outer casing 10 has not been shown. It is contemplated that any conventional mounting means may be used. The clutch control rod 26 may be set manually to engage the motor with the agitator 17, so that the clothes are washed by the short vertical pulsations of the agitator. After the washing operation is completed, the rod 26 is moved to engage the motor with the spinner shaft 32, which in turn spins the tub 14, thus causing the clothes to be dried, the water being discharged into the drain trough 16 from whence it is discharged by proper drain connections, not shown, either into the sewer, or into a receptacle where the suds are maintained for the next washing.

However, the foregoing mechanism is particularly advantageous when used with automatic 40 controls such that once the clothes are placed in the tub, with a sufficient washing compound, the controls can be set so that the clothes are given a washing operation, a centrifugal drying action, a first rinse, a second drying action, a 45 second rinse, and a last drying action without any further attention from the operator.

The Scotch yoke 30 is somewhat diagrammatically shown and is of the type which permits the agitator 17 to rotate with the tub 14 when 50 the tub is rotated. The Scotch yoke mechanism is a well-known mechanical movement and therefore is not illustrated in detail. It is of such a character that it permits the crank-pin 29 to follow its orbital movement, imparts to the agitator shaft 31 a vertical reciprocating movement,

and permits the agitator 17 to rotate with the tub 14 when the tub is rotated. By virtue of the construction hereinabove described, it is obvious that the agitator 17 does not serve as a drag on the tub 14 and the clothes in the tub during the spinning operation. It is also obvious that there is less danger of the clothes being torn or the driving mechanism being damaged when the agitator and the tub spin together. Pin 31a carried by the spinner shaft 32 projects into the slot 31b in the shaft 31 whereby the agitator 17 rotates with the tub 14. The crank-pin 29 drives the Scotch yoke mechanism by means of a horizontal slot bearing 51, as is well known. Relative rotation between the agitator drive mechanism and the agitator 17 is obtained by a vertically keyed, but rotationally free, joint in the agitator shaft 31 either at its upper end 52 or its lower end 53. For purposes of illustration, the lower end of the shaft 31 has been shown as provided with a collar 53a which serves to vertically key the shaft 31 to the Scotch yoke 30. The shaft 31 and the collar 53a may be free to rotate with respect to the Scotch yoke 30. In order to simplify this disclosure, details which are deemed obvious to persons skilled in this art have been omitted.

The tub 14 is filled with liquid nearly to its top. When clothes are placed in the tub and the agitator is reciprocated at the rate herein stated, a very efficient washing agitation is obtained. The agitator tends to impart a "smoker's ring" or torroidal movement to the clothes and water, and this flexes the clothes continuously during the washing operation and thus frees the dirt from them. The outer edge of the ring 18 also tends to impart a rubbing action on the clothes.

This action is obtained because of the quick vertical reciprocation of the continuously submerged lower edge of the agitator 17. The ring 18 acts as a "duck's foot" and washes the clothes mainly by the strong pulsating radially outwardly directed water currents at the bottom of the tub which impart the "smoker's ring" agitation to the main body of water.

With my improved mechanism any one or more of the usual washing operations can be performed without removing the clothes from the tub. By driving the agitator from the underside, the top of the tub is free for easy manipulation of the clothes.

While the form of embodiment of the invention as herein disclosed, constitutes a preferred form, it is to be understood that other forms might be adopted, all coming within the scope of the claims which follow.

What is claimed is as follows:

1. A washing machine comprising a support, a vertical bearing sleeve carried by said support, a hollow shaft having a bearing in said sleeve, a vertically reciprocable shaft in said hollow shaft, a liquid holding tub supported above said support by said hollow shaft, an agitator in said tub supported and actuated by said reciprocable shaft, a flexible bellows forming a liquid seal between said tub and reciprocable shaft, transmission mechanism on said support selectively connectible to rotate said hollow shaft or to reciprocate said reciprocable shaft, and a motor on said support drivingly connected to said transmission mechanism.

2. A washing machine comprising a support, a vertical bearing sleeve carried by said support, a hollow shaft having a bearing in said sleeve, a vertically reciprocable shaft in said hollow shaft, 25 a tub supported above said support by said hollow shaft, an agitator in said tub supported and actuated by said reciprocable shaft, a flexible bellows forming a liquid seal between said tub and reciprocable shaft, transmission mechanism on said support selectively connectible to rotate said hollow shaft or to reciprocate said reciprocable shaft, and a source of power drivingly connected to said transmission mechanism.

3. A washing machine comprising a support, 35 a vertical bearing sleeve carried by said support, a hollow shaft having a bearing in said sleeve, a vertically reciprocable shaft in said hollow shaft, a tub supported above said support by said hollow shaft, an agitator in said tub supported and actuated by said reciprocable shaft, means including a flexible bellows forming a liquid seal between said tub and reciprocable shaft, transmission mechanism on said support selectively connectible to rotate said hollow shaft or to reciprocate said reciprocable shaft, a source of power drivingly connected to said transmission mechanism, and means preventing relative rotation between said agitator and said tub.
